UNITED STATES PATENT OFFICE

MAURICE E. DAVIS, OF GRAND RAPIDS, MICHIGAN, ASSIGNEE, BY DIRECT AND MESNE ASSIGNMENTS, OF SEVENTY ONE-HUNDREDTHS TO HARRY E. MOYSES, OF NEW YORK, N. Y., AND THIRTY ONE-HUNDREDTHS TO ABE J. WARSAW, OF GRAND RAPIDS, MICHIGAN

APPARATUS FOR COATING MATERIAL

Application filed June 11, 1930. Serial No. 460,358.

This invention relates to apparatus for coating material which may be in separate pieces of non-uniform thickness or of irregular shape such as tire patches.

5 The general purpose of the invention is to provide an apparatus for effectively applying a coating to one side only of such material such as to the convex side of concavo-convex skived tire patches.

10 A further purpose of the invention is to provide means associated with the coating apparatus for depositing the coated articles on a surface such as a conveyor belt with their coated faces uppermost.

15 The foregoing and other purposes of the invention are attained in the apparatus illustrated in the accompanying drawings and described herein. It is to be understood that the invention is not limited to the specific 20 form thereof shown and described.

Of the accompanying drawings,

Figure 1 is a rear view of apparatus embodying the invention; and

25 Figure 2 is a section on line 2-2 of Figure 1.

Referring to the drawings, the numerals 10, 10 designate suitable supports on which are mounted brackets 11, 11 in which are journaled a pair of cooperating rolls 12 and 13.

30 Roll 12 is journaled in bearing blocks 14, 14 arranged in slots 15, 15 in bracket members and roll 13 is journaled on a spindle 16 secured in blocks 17, 17 also slidably in slots 15.

35 Blocks 14 and 17 are spaced apart by spacer bars 18, 18 about which are coil springs 19, 19 normally tending to urge blocks 14 and 17 apart. A screw 20 threaded through a plate 21 on top of each bracket 11 is adapted to hold blocks 17 against spacers 18 against the expansive actions of springs 19.

40 Roll 12 dips in a reservoir 22 for the coating material 22^a and is arranged to apply the coating of material thus formed thereon onto the under side of a patch or the like passed between the rolls. Roll 12 is of soft yielding material whereby it is adapted to conform to the contour of the material such as the patches which are passed between the rolls.

45 Roll 12 may be driven by a pulley 12^b on its shaft 12^a, this shaft having a gear 23 thereon meshing with a gear 24 secured to roll 13 to drive the latter.

50 Brackets 25, 25 may be secured on shaft 16 to support a guide bar 26 over which patches P may be fed to the rolls as shown and these brackets may also support a scraper 27 pivotally mounted as at 28, 28 and adapted to be urged against the roll 13 by screws 29, 29 threaded through plate 30 into engagement with projecting lugs 31, 31 attached to the scraper 27.

55 Arranged in the path of the issuing patches P rearwardly and beneath the rear right of the rolls 12 and 13 are a number of rotary spiders 32 adapted to support and feed the issuing patches in such a way as to flip them over onto their faces as they drop from the rolls onto a surface such as conveyor belt 33. The spider 32 may be mounted on a shaft 32^a adapted to be received in any one of a number of bearing receptacles 34, 34 to adjust the position of the spiders toward or from the rolls to adapt the machine for patches of different sizes. The shaft 32^a may be driven by a pulley 35 over which may be trained a belt 36 which is driven by a pulley 37 on shaft 12^a.

60 To prevent adherence of the coated material or patch to the rollers 13 and 14 a series of fingers 38, 38 and 38^a, 38^a are provided on the rear side thereof extending tangentially into proximity to the periphery thereof. These fingers 38 may be carried by supports 39, 39 on a cross bar 40 and the fingers 38^a may be directly carried on a bar 40^a, the bars 40 and 40^a extending between the bracket members 11.

65 In operation, the patches P are fed to the machine as shown in Figure 2 being engaged on bar 26 and inserted between the rollers which draw the patches through, embedding the same in the rubber roll (Figure 1), the roll 12^a applying a coating to the lower or convex surface only of the patches. The coating material applied to roll 13 about the patches is scraped off by scraper 27 so as not to be applied on the upper surfaces thereof.

70 As the patches pass from the rolls the lead-

ing ends engage the spider 32 which so feed the patches outwardly that upon issuing from the rolls the patches are flipped over onto their non-coated faces (Figure 2) on conveyor 33.

It will be apparent that the invention is not limited either to the specific use thereof or to the particular embodiment thereof. Accordingly, modifications thereof may be resorted to without departing from the spirit thereof or the scope of the appended claims.

What is claimed is:—

15. Apparatus for coating the convex face only of concavo-convex tire patches, said apparatus comprising a pair of driven rolls, the lower roll of which has a yielding surface to conform to the surface of a patch passed between the rolls, means for applying a layer of coating material to the yielding roll, means for removing such material from the other roll, a receiving surface positioned below the rolls, and rotary means adjacent the delivery side of the rolls adapted to engage the pieces issuing therefrom and impart such a motion to the pieces that they alight on the receiving surface with coated side uppermost, the pieces being unsupported between the said rotary means and the receiving surface.
20. Apparatus for coating the convex side only of concavo-convex tire patches, said apparatus comprising a pair of driven rolls, the lower roll of which has a yielding surface to conform to the surface of a patch passed between the rolls, means for applying a layer of coating material to the yielding roll, means for removing such material from the other roll, a receiving surface positioned below the rolls, and means comprising rotary
25. spiders adjacent the rear side of the rolls for engaging the pieces issuing therefrom and flipping them over so that they fall onto the receiving surface on their uncoated faces, the pieces being unsupported between the spiders and the receiving surface.
30. 3. A combination as defined in claim 2 in which the receiving surface is a conveyor.

MAURICE E. DAVIS.
